DESIGN FOR A CLOCK

Spero George Kooluris, Newark, and Leslie Fox,
Cedar Grove, N. J.

Application October 11, 1939, Serial No. 87,624

Term of patent 3½ years

To all whom it may concern:

Be it known that we, Spero George Kooluris and Leslie Fox, citizens of the United States and residents, respectively, of Newark and Cedar Grove, in the county of Essex and State of New Jersey, have invented a new, original, and ornamental Design for a Clock, of which the following is a specification, reference being had to the accompanying drawing, forming part thereof.

Figure 1 is a front elevational view of a clock embodying our design.

Figure 2 is a side elevational view of the clock, and

Figure 3 is a top plan view thereof.

We claim:

The ornamental design for a clock, as shown.

S. GEORGE KOOLURIS.

LESLIE FOX.
